UNITED STATES PATENT OFFICE.

CHARLES H. CAMERON, OF CHICAGO, ILLINOIS.

CUSHIONED CAR-WHEEL.

SPECIFICATION forming part of Letters Patent No. 623,883, dated April 25, 1899.

Application filed January 28, 1899. (Serial No. 703,736. (No model.)

To all whom it may concern:

Be it known that I, CHARLES H. CAMERON, a citizen of the United States, residing at Chicago, in the county of Cook and State of Illinois, have invented certain new and useful Improvements in Cushioned Car-Wheels; and I do declare the following to be a full, clear, and exact description of the invention, such as will enable others skilled in the art to which it appertains to make and use the same.

My invention relates to certain improvements in cushioned car-wheels, and more particularly to that class of car-wheels having a continuous annular elastic cushion interposed between the rim and the body of the wheel; and the object is to provide a simple, durable, and effective wheel of this character.

To this end the invention consists in the construction, combination, and arrangement of the several parts of the device, as will be hereinafter more fully described, and particularly pointed out in the claim.

In the accompanying drawings the same reference characters indicate the same parts of the invention.

Figure 1 is a perspective transverse section of a cushioned car-wheel embodying my improvements. Fig. 2 is an enlarged detail section of the same.

1 denotes the hub, and 2 the body portion, of the wheel, the periphery of which terminates in an annular concentric flange 3, the inner face of which is arranged diagonal to the plane of the wheel and at an approximate right angle to the contiguous face of a corresponding flange 4 on the concentric disk plate 5, which encompasses the hub, and is removably secured to the corresponding body portion 2 by means of the bolts 6 and jam-nut 7.

8 denotes the rim, and its inner face is formed with an annular rib 9, which is approximately right angular in cross-section, so that its diagonal faces will lie parallel with the opposed faces of the flanges 3 and 4.

10 denotes the elastic cushion, which consists of an annular rubber ring interposed between the rib 9 and the flanges 3 4 in such a manner that there will be an expansion-space *e* formed between the bend in the cush-

ion and the meeting edges of the flanges 3 and 4.

13 denotes one of a series of crescent or C shaped conductor-bonds which are inserted in the cushion at suitable intervals, and their free ends come in contact with and establish electrical communication between the body portion of the wheel and the rim, so that when wheels so constructed are fitted to trolley-motors an uninterrupted path for the return current to the rail is provided through the cushioned wheel.

This construction of the wheel and rim and the manner of inserting the cushion not only conduce to the elastic or cushioning properties of the wheel, but also prolong the life of the cushion, as it is allowed to expand equally in opposite directions, outwardly between the outer edges of the flanges 3 and 4 and the rim and inwardly into the expansion-space *e*, whereas if there were no expansion-space provided the central portion of the cushion would be compressed to such a degree as to crush the life out of it and kill its elastic properties. Another important advantage of this space *e* is that it prevents the cushion from "pinching" between the meeting edges of the contiguous concentric flanges when assembling the wheel and bringing the parallel disks together by means of the bolts.

The accompanying drawings show my invention in the best form now known to me; but many changes in the details may be made within the skill of a good mechanic without departing from the spirit of my invention as set forth in the claim at the end of this specification.

Having thus fully described my invention, what I claim as new and useful, and desire to secure by Letters Patent of the United States, is—

In a cushioned car-wheel, the combination with the rim 8, formed with the internal annular rib 9, having plane meeting faces, of the body portion 2, formed with the annular diagonal flange 3, the concentric disk plate 5, formed with the corresponding annular diagonal meeting flange 4, the continuous annular cushion 10, interposed between the plane

meeting faces of the rib 9 and the plane meeting faces of the flanges 3 4, and the C-shaped resilient conductor-bond, seated in said cushion and having its free ends in contact with the body portion and the rim of the wheel respectively, substantially as and for the purpose set forth.

In testimony whereof I have hereunto set my hand in presence of two subscribing witnesses.

CHARLES H. CAMERON.

Witnesses:

I. R. GIRLIN,

OLIVER P. HUBBARD.
